JAMES C. LEDBETTER, OF BROOKLYN, NEW YORK, ASSIGNOR TO THE THOMAS & BETTS CO., OF ELIZABETH, NEW JERSEY, A CORPORATION OF NEW JERSEY.

CABLE CONNECTER.

Application filed January 22, 1924. Serial No. 687,776.

This invention relates to combination outlet boxes and cable connectors, and more particularly to improvements in connectors for use in anchoring electric cables or conduits 5 to electric box fixtures, such as outlet boxes, switch boxes, cable boxes, and the like.

An object of the invention is to produce an improved cable connector of simple structure capable of being manufactured at low 10 cost, and which positively functions to securely fasten a cable to said box, as well as produce a cable connector which fits standard round knockout holes in boxes of present-day use; and an important feature of 15 my connector invention resides in the two part construction together with the ability thereof to cover over the box opening by closely surrounding the cable.

A further object of the invention is to 20 produce a simple plate and shell connector structure embodying two plain stampings which, when assembled with clamping means, such as a screw, the said connector functions to simultaneously fasten a cable as well as 25 anchor itself to a box. For this purpose the connector employs one operating means and is so formed that the box hole edge is exposed directly to the cable.

The accompanying drawing illustrates an 30 embodiment of the invention serving to illustrate the principle and structure thereof as well as the mode of operation; and the connector may be subject to modifications in certain respects without departing from the 35 scope and principle of the invention.

Figure 1 shows a top open view of an 40 electric fixture box joined to a cable through the agency of an improved connector constituting the important part of this invention; and Figure 2 shows a side view thereof.

Figure 3 illustrates a sectional view taken on the line 3—3 of the drawing; and Figure 4 shows a sectional view taken on the line 4—4 of the drawing.

Figure 5 illustrates a cluster view of the 45 two-part connector constituting an important part of this invention, the said view illustrating rear, side, and top projections of the connector.

The last three figures of the drawing illustrate a slightly modified structure in which 50 substantially the same principle of the invention is involved.

Figure 6 shows a longitudinal section view 55 through a box with the two connector parts

in section mounted in the box knock-out opening.

Figure 7 is a sectional view on the line 7—7; and Figure 8 is a sectional view on the line 8—8.

To those conversant with the art, it is appreciated how present-day boxes B are ordinarily made with standard round knock-out holes H into which the cable C carrying wires W is fastened by connectors; and as 65 aforesaid it is one of the principal objects of this invention to produce simple and inexpensive connectors for fastening the cable in the box knock-out opening.

With particular reference to the construction of the connector itself, it is explained that this connector is preferably constructed in two separable parts each of which is provided with box hole edge anchorage means 70 as notches or grooves which overlap and engage the box knock-out opening thereby holding the parts in spaced relation, and the cable C is inserted therebetween after which a clamping or operating device, such as a screw, impinges the cable to lock all 75 parts together.

The two connector parts are made with companion cover plates 10 and 11 such that when brought together and assembled in the 80 box, the two said plates provide a cover 85 10—11 fitting substantially tight and close over that portion of the knock-out opening H of the box which is not covered up by the cable C. Furthermore, each co-operating cover plate 10 and 11 is made with a 90 substantially half-round or arcuate opening 12 through which the cable C passes when the parts are assembled. The two plates 10 and 11 rest or abut one side of the 95 box B and embrace the circular wall of the cable to cover up the box opening H as aforesaid.

A cable rest or sleeve in the form of an 100 arcuate wall or in the form of a substantially half-round projecting part or shell 13 is 105 made integral with one cover plate, and in this instance the part 13 is integral with the plate 11 and has its circular wall 13 coincidently formed with the arcuate opening 12 made in the said plate 11. A bushing rim 14 is made on the outer end of the supporting shell or sleeve part 13 and the cable end C stops or rests against this bushing when the parts are assembled.

The sleeve or shell 13 is disposed inside 110

the box and held in position by a plate or lug 15 which projects through the box opening. This lug or plate is made with a pair of oppositely punched or formed box hole edge grooves or notches 16, the said notches being formed in the plate 15 adjacent the plate 11 such that the box wall B fits in the notches 16 and abuts the surface of the cover plate 11. By introducing the plate 10 part 15 through the box hole H, the notches 16 are readily engaged over the edge of the box hole thereby positively holding the part in place.

The other part of the connector may also 15 comprise a cover plate element 10 as hereinbefore described and the said plate includes a screw supporting end 18 similar to the one hereinbefore described. The plate 10 and end or lug 18 are formed substantially at 20 right angles and box edge notches 19 are formed in the lug 18 adjacent the cover plate 10, there being two notches 19 oppositely arranged as shown. A pressure or clamp screw 20 is threaded through the lug 25 18 and preferably to one side thereof which causes the screw to impinge and screw into the cable C at substantially a tangent thereto, thus avoiding crushing the cable.

The box hole edge notches 16 and 19 30 formed in the separable connector parts serve to hold the two cover plates 10 and 11 in alignment close to the box wall surface when the parts are assembled. It is important to note that the width of the two 35 projecting lugs or plates 15 and 18 is somewhat less than the diameter of the knock-out hole H in the box. Two projecting parts 15 and 18 being substantially small in size are readily projected through the box opening, preferably one at a time when it comes 40 to assembling the parts in a box. The notches 16 and 19 leave exposed a portion of the box hole edge so that the cable C may rest against said exposed portion and is 45 gripped and fastened thereby.

In assembling the box and parts, the cable C is inserted through the box hole H with the two connector parts oppositely located thereby positioning the cable between 50 the two parts. The clamp screw 20 is set up tightly against the cable C which serves to rigidly hold the two connector parts in position as well as fasten the cable C to the said connector parts. The single screw not 55 only anchors the connector in the box hole by seating the box hole edge in the notches 16 and 19 but simultaneously fastens in the cable as well.

Referring now to Figures 6, 7 and 8, a 60 substantially half-round or arcuate stamping 25 is made with a rim 26 at one end in form of a bushing, and is punched centrally to form a groove or opening 27. The part 25 is inexpensive to manufacture by virtue 65 of its simple design, and it is apparent how

it is capable of being cast or punched with economy. The punched or cast groove or slot 27 is placed over the box hole edge H thereby exposing an arc of the box edge within the inner circular wall of the shell 70 25. Since the diameter of the shell 25 is less than that of the hole in the box, it follows that the box hole edge H is eccentrically exposed within the inner wall of the shell 25. Thus when a cable C is placed in the 75 shell or cable rest 25 it is engaged by the sharp projecting exposed edge H of the box B.

A flat plate stamping 28 is punched with box hole edge notches 29 similar to the 80 structure already described, there being two notches 29 formed in alignment and embracing the box wall B. A clamp screw 20, as already described, is carried by the plate 28 and is directed toward the cable and 85 preferably the plate may be curved or bent downwardly to cause the screw 20 to point at an angle towards the box edge exposed in the cable rest 25 which more effectively pinches the cable wall C into the sharp exposed arc of the box opening edge or rim. 90

The connector parts 25 and 28 are placed 95 diametrically opposite in the box hole H with the cable C introduced therebetween, whereupon the screw 20 is driven downwardly against the cable which forces the cable against the opening H exposed through the shell 25 thus rigidly anchoring all parts together.

It is apparent that I have produced a 100 connector which employs one operating means as a screw to perform several functions namely, that of anchoring the connector in the box hole, and that of fastening the cable in the connector and box hole. Furthermore, the box hole edge itself is made 105 to perform several functions namely, that of gripping against the cable, and that of seating into the connector anchorage means. 110

What I claim is:

1. Cable and box connecting means comprising, a box having a cable and connector receiving hole, a pair of connector members disposed in the box hole and including box hole edge receiving notches located substantially at the center in one member which notches engage and leave exposed the box hole edge, and a screw threaded through one member to grip against a cable received between the members and to seat the notches of both members against the box hole edge and to force the cable against the exposed box hole edge. 115

2. A connector comprising a pair of connector members each of which includes box hole edge anchorage notches which leave exposed a box hole edge in the connector, and a screw threaded through one connector member and directed toward the other connector member to grip a cable between the 120 125 130

two members and against the exposed box hole edge.

3. A connector comprising, separate connector members adapted to fit into a box hole and including anchorage notches to receive the box hole edge, a screw threaded through one member and directed toward the other member, and a portion included at substantially right angles on each member adjacent the notches and extending toward the cable, each portion being provided with a semi-circular opening such that when placed together there is formed a cable receiving opening through the two portions. 15

10 4. A connector comprising, a pair of separate members adapted to fit into a box hole

and including anchorage notches to receive the box hole edge, a screw threaded through one member and directed toward the other member, and a portion included at substantially right angles on each member adjacent the notches and extending toward the cable, each portion being provided with a semi-circular opening such that when placed together there is formed a cable receiving opening through the two portions. 20

In testimony whereof I affix my signature.
JAMES C. LEDBETTER.
